M. EBINGER

FURRING NAIL

Filed June 16, 1923

FIG. 1

FIG. 2

FIG. 3

FIG. 4

INVENTOR
MICHAEL EBINGER

BY

ATTORNEY

Harry Johnson

UNITED STATES PATENT OFFICE.

MICHAEL EBINGER, OF OAKLAND, CALIFORNIA.

FURRING NAIL.

Application filed June 16, 1923. Serial No. 645,983.

To all whom it may concern:

Be it known that I, MICHAEL EBINGER, a citizen of the United States, residing at Oakland, in the county of Alameda and 5 State of California, have invented certain new and useful Improvements in Furring Nails, of which the following is a specification.

My invention is an improved furring nail. 10 The object of my invention is to provide a furring nail which is simple in construction, and inexpensive to manufacture.

Another object is to provide a shield which will close the hole made by the nail and 15 thereby prevent moisture from entering the wall.

Further objects and advantages will be more specifically pointed out in the following detailed description.

20 In the annexed drawing in which my invention is illustrated:

Figure 1 is a front view of my nails in position on a wall.

Figure 2 is an enlarged front view of my 25 furring nail.

Figure 3 is a sectional view taken on the line 3—3 of Fig. 2.

Figure 4 is a side view of my nail.

Referring more particularly to the drawing, my furring nail consists of a head 1, which may be of any desired angular shape, and is here shown as square. A notch 2 is 30 cut in each side of the head 1, and a nail 3, the head of which is counter-sunk in the head 1, extends through said head.

A plate 4, which is preferably formed of sheet metal, is positioned at the rear of the head 1, and the nail 3 extends through it and

35 into the wall 5, thus holding the head and plate securely in position. This plate, being held securely against the wall will prevent any moisture from entering through the hole formed by the nail 3, thus obviating one objectionable feature of most nails.

The wire mesh 6 is spread over the wall 15 and is held in position by nails 7, which are positioned in the notches 2, and are driven through the plate 4 into the wall 5, the ends 30 being bent downwardly over a strand of the wire as shown in Figs. 2 and 3.

The edges of the head 1 are bevelled inwardly as shown at 8. The cement wall coating will flow around the heads 1 and the edges 8 thereof will form a further anchoring means in addition to the wire 6.

Having described my invention, I claim:

1. A furring nail comprising an angular shaped head, and a nail extending through said head, whereby the head is secured to a wall, the sides of said head being bevelled 30 rearwardly.

2. A furring nail comprising an angular shaped head, said head having notches in the sides thereof adapted to receive a nail, a plate back of said head and a nail adapted 35 to extend through the head and the plate and into a wall.

3. A furring nail comprising an angular shaped head, said head having notches in the sides thereof adapted to receive a nail, and a nail extending thru said head whereby the head is secured to the wall, the sides of said head being bevelled inwardly.

In testimony whereof I affix my signature.

MICHAEL EBINGER.
